UNITED STATES PATENT OFFICE.

HARRIS G. WARD, OF VASHON, WASHINGTON.

DISPLAY DEVICE.

Application filed October 15, 1925. Serial No. 62,539.

My invention relates to a display device, and more particularly to the class of such devices wherein a series of independent display sheets are maintained in a magazine, 5 to be removed therefrom one at a time and independently exhibited, and then returned to the magazine.

One of the objects of my invention is the provision of a novel method of handling 10 such display sheets, and the provision of a novel mechanism for carrying out the method, whereby flexible sheets are maintained in inverted position in the magazine and are removed therefrom one at a time, 15 inverted into display position and finally re-inverted and replaced at the back side of the magazine, thence moving bodily forward through the magazine.

A further object is the provision in a display device of two types of displays, one 20 comprising a series of different displays to be exhibited in succession, and the other comprising a display for an underlying basic idea which is displayed recurrently, to 25 the end of emphasizing its message through constant repetition.

A further object is the provision of satisfactory, simple operating and control means 30 for the various display mechanisms, and the provision of such operating and control mechanisms as will give satisfactory and continued service without the necessity for frequent adjustment or repair.

Other objects reside in the provision of 35 suitable mechanical structures for carrying out the principles of my invention as further described in this specification.

My invention comprises the novel mechanism and the novel parts and arrangements, 40 as shown in the accompanying drawings, described in the following specification, and particularly defined by the claims terminating the same.

In the accompanying drawings I have 45 shown an embodiment of my invention which constitutes its present preferred form.

Figure 1 is an elevation of the display device as viewed by the observer, and Figure 2 is a like elevation showing a different aspect of the display;

Figure 3 is also an elevation with part of the framework removed, and in section showing the display in process of change;

Figure 4 is a side elevation with part of 55 the framework removed, and in section il-

lustrating the general arrangement of the parts;

Figure 5 is a rear elevation of the drive mechanism;

Figures 6 and 7 are like sectional views 60 transversely of the main control mechanism, illustrating parts in different positions and relations.

Fig. 8 is a detailed sectional view taken 65 on line 8—8 of Fig. 7.

In one aspect my invention is concerned 70 with the presentation of a message which it is desired to drive home to the observer, and associated therewith is the presentation to the observer of a series of different messages, views, pictures or the like, relating to 75 the basic or recurrent idea and designed to retain the interest of the observer. It is recognized in the psychology of advertising that a message, to be retained by the observer, must be driven home by constant repetition. It is also true that the observer's attention must be retained and he must be diverted from the sameness of the repetition 80 by changes in the matter presented, or in its form.

My invention is designed to take advantage 85 of these principles of advertising, and to present the basic idea in the form of a display which is only before the observer during periods intervening between the display calculated to retain his interest, but which is constantly being repeated. This, 90 in the present embodiment, may be done by presenting the recurring idea upon a display sheet which is ordinarily withdrawn and out of sight, as for example, upon the sheets 9 and 9' which will part to permit the 95 observance of the several independent and flexible sheets typified by the sheet 1. The sheets 9 and 9' are suitably mounted to be withdrawn, as upon the rod 91, and are controlled for movement in some suitable manner, as, for example, by means of the continuous cable 92 passing over the sheave 100 or drum 93 and secured to the sheets 9 and 9' at the points 90 and 90' respectively. By giving the sheave 93 an intermittent movement in opposite directions, the sheets 9 and 9' are alternately opened and closed. They 105 may be weighted at their lower ends, particularly at their adjoining corners, as indicated at 94, to insure that they will hang smoothly and will come together. The mechanism, including the shifting display 110

control means, to be described hereafter, may be enclosed within a suitably embellished framework indicated in general by the numeral 95, which may bear a slogan 5 which is continuously presented, as indicated in Figures 1 and 2. Figure 1 represents the sheets 9 and 9' drawn together in closed position to present the recurring message, and Figure 2 represents the device 10 with the sheets 9 and 9' withdrawn, or in open position, to present one of the changeable display sheets 1. Figure 3 represents these in process of change.

The changeable displays are preferably 15 supported on flexible sheets 1, each of which is provided with a rod 10 and a rod 11 extending transversely across the top and bottom edge, respectively, of the sheet. To retain a number of these sheets, a magazine 20 is provided, this magazine in the present embodiment being shown as composed of two pairs of inclined channel-like tracks 20 and 21, respectively. The ends of the rods 10 are receivable in the tracks 20, and the ends 25 of the rods 11 in the tracks 21, wherein they are free to slide toward the lower end of the tracks. Thus supported, the sheets are in inverted position with their top edge lowermost.

Figures 6 and 7 illustrate one side only 30 of the display-handling and control mechanism, it being understood that the opposite side is merely a duplication thereof. Guides are provided for engagement with the rods 35 10 and 11 to invert them, and then to guide them into display position, then to re-invert them and to deliver them to the receiving point of the magazine, the magazine being represented in general by the numeral 2. 40 Such guides may comprise the channel-like tracks 3 and the rollers 30 associated therewith. These tracks or guides include the delivery point of the magazine and its receiving point. Preferably, an initial portion 45 31 of the track extends vertically along the lower side of the magazine 2, communicating with its tracks 20 and 21. This portion 31, the chief function of which is to receive the bottom pin 11 of a sheet, is formed in such a manner that it restrains this rod 11 50 from falling. This may conveniently be accomplished by providing one side thereof, as 52, yieldable as by the pin and slot connection 53 and pressed, as by springs 54, 55 towards the opposite side of the track to frictionally hold and restrain the rod 11.

Selector mechanism is provided adjacent the delivery ends of the magazine tracks 20 and 21 to deliver a single sheet from the magazine and to retain the others until the selected sheet has been fed forward. Such means may comprise the external vertical link 42 (see Figure 4) controlled for vertical reciprocation by a member 4 comprising in 60 effect a lever pivoted at 43, having one end

44 adapted to be engaged by suitable means to operate the selector, and having its other end 45 positioned to be engaged by the same means to insure the return of the selector mechanisms to their normal closed position. 70 This link 42 has lugs or gate members 40 at its lower end, and 41 at its upper end, both projecting inwardly from the link 42 sufficiently to engage the rods 10 and 11 respectively, as a sheet emerges from the magazine 75 2. The end 45 of the lever 4 may be connected to or engaged with the link 42. As the member 44 is displaced, as shown in Figure 7, the gate portions 40 and 41 of the selector are raised out of engagement with the ends of the respective rods 10 and 11, to permit the movement of the single rods 10 and 11 from the magazine, and upon downward movement of the gate members 40 and 41, these rods are moved downward slightly 85 and the ends of the tracks 20 and 21 are closed.

Feed means are provided for then engaging the sheet and advancing it, these comprising in the present mechanism a pin 5, 90 which is movable in a closed path which includes the delivery point of the magazine 2 and its receiving point. As shown herein, the pin 5, of which two are preferably used, is carried by a chain 50 which is carried upon sprockets 51 co-axial with the rollers 30 and 51', outside of the path of the display sheets. In the main, however, the run of the chain 51 coincides with the tracks or guides 3 for the display sheet. Thus the top rod 10 of a sheet which has just been removed from the magazine, is positioned in the path of the pin 5 and, as seen in Figure 7, the pin 5 in the lower right hand corner continuing its advance in the direction of the arrow, will 100 engage the rod 10. In Figure 6 the pin is shown as engaged beneath the rod 10 in the process of advancing the display sheet 1 to display position. The sheet 1, it will be seen, is passed beneath the roller 30 to reverse 105 its top for bottom.

It will be noted in Figure 7 that a member 6 is pivoted at 60 adjacent the point where the rod 10 is picked up by the pin 5 and is permitted a limited movement between the sides 110 of the guide 3. This acts as a backing to prevent the advancing pin 5 from pushing the rod 10 upward and passing therebeneath. It insures that the rod 10 will be carried directly forward in advance of the pin 5. It 115 can then be thrown downward by the following pin 11 to permit passage thereof into the guide 3. It will be seen also in Figure 7 that the pin 5 engages the member 44 to operate the selector mechanism and that the end 45 of the lever 4 is positioned in the path of the pin 5 so that if the selector members have not resumed their normal closed position, they will be returned to such position by the pin 5 as it engages the end 45 and prior 120 125 130

to engagement of the pin with the rod 10. This insures closing of the magazine prior to advance of the delivered display sheet.

The chain 50 and pin 5 are advanced in 5 the direction of the arrow in Figures 6 and 7, to carry a sheet delivered from the magazine into display position at the front of the magazine. Here it is held in position, the cover sheets 9 and 9' being then opened and 10 finally closed, following which the pin 5 resumes its advance and moves the display sheet from display position, reversing it top for bottom and bringing it to the receiving point of the magazine 2. In the meantime 15 the second pin 5 has released and then picked up a second display sheet and has advanced it to the display position, whereupon the sheets 9 and 9' are opened. Figure 6 shows a sheet being advanced into the display position and a sheet being moved therefrom. Figure 7 shows a sheet immediately after beginning its movement away from the display position, and shows a pin 5 in the first step of releasing a new sheet to be 20 advanced thereby. Suitable intermittent control mechanism is provided for operating the chain and for operating the sheets 9 and 9' in the manner described, and this mechanism will be described hereinafter.

Owing to the manner of handling the sheets, moving them bodily forward through the magazine, it is necessary that means be provided which will permit the top rod 10 to pass the upper track 21, but which will insure 35 that the bottom rod 11 is intercepted. I have, therefore, provided switch mechanism positioned adjacent the path of the pin 5 and at the receiving point of the track 21. This comprises a lever 7 pivoted at 70 and 40 having one arm 71 movable across the path of the rods and from such path. The other arm 72 is connected by links and levers 73, 74 and 75 to a control lever 76, pivoted at 77. A striker member 78 carried by the switch 45 member 7, is movable into the path of the pin 5 when the switch and point 71 are moved out of the path of the rods and vice versa. I have also provided a diverter 79 fixedly 50 positioned across the path of the rods and at the receiving end of the track 20.

As the display sheet moves from the display position, as shown in Figure 7, the switch 7 remains in the position shown in that figure. As the rod 10 passes the switch 55 point 71, it continues downward in the guide 3 but the striker 78 is engaged by the pin 5, which projects sufficiently to engage it, and the switch is thrown into the position shown in Figure 6. In this position of the switch 60 point the following rod 11 is intercepted, this interception occurring at about the time that the rod 10 reaches the diverter 79. The result is that these two rods are moved out of the guide 3 and into their respective tracks 20 and 21, the pin 5 continuing in line

with the back run of the chain. The same pin continuing, strikes the member 44, releases a new sheet and continues picking up the sheet. In passing it engages the member 76, which is connected to the switch 7, and 70 resets the switch in the position shown in Figure 7.

A single motor M may be employed to operate all of the movements, this being connected through suitable reduction gearing 75 and enclosed within the casing 80 to drive a master gear 8. This gear 8 is provided with pins 81 and 81' spaced angularly and placed at different radial distances. A wheel 82, having opposite radial slots 83 and 83', is connected to the drum or sheave 93 and is positioned so that its slot 83 will be engaged by the pin 81, or so that its slot 83' will be engaged by the pin 81'. Thus, by alternate engagement of the pins 81 and 81' 80 with the respective slots 83 and 83', the sheave 93 is moved alternately in a counter-clockwise direction and then clockwise to move the sheets 9 and 9' into open or closed 85 position.

A wheel 84 is likewise positioned adjacent the master gear 8 and is provided with opposite radial slots 85 which are positioned to be engaged by either one, but not both of the pins 81 and 81', preferably the latter. 90 This may be accomplished by varying slightly the radial distances of the sheave 93 and wheel 84, or by varying the lengths of the pins and the spacing of the sheave 93 and wheel 84 from the gear 8. This wheel 84 is 95 so disposed that engagement of the pin 81' with either slot 85 will rotate the wheel 84 through a half revolution, successive engagements of the same pin 81' rotating the wheel 100 in the same direction. The pin 81 does not engage a slot 85, if the pin 81' engages therein, or vice versa. This wheel 84 is connected as by the beveled gears 89 and the chain 86 passing over sprockets 87 and 87' to the shaft 88, which carries the drive gear 105 51' for the chain 50. By these or equivalent means the chain is intermittently advanced in between periods when the sheets 9 and 9' 110 are in closed position.

It will be understood that the details of 115 my invention can be widely varied, and I do not wish to be understood through my description of a preferred embodiment, as limiting myself thereto in any way, except as defined by the claims terminating this 120 specification.

Essentially, my invention comprises in 125 one aspect the employment of the recurring display sheets which present a basic message during intervals that the interest-retaining sheets are being shifted. In another aspect the essence of my invention lies in the handling of the independent display sheets in the manner described, moving them bodily forward in inverted position through a mag-

azine, picking them up and inverting them while moving them to display position, again inverting them and finally delivering them inverted to the rear side of the magazine.

While it is not essential, I prefer that pins 55 be provided in pairs, attached to and movable with the chain 50. These pins 55 are spaced somewhat from each other and are spaced from the corresponding pins 5 in such a manner that these will receive between them the following rod 11 of the display sheet which is being advanced by the corresponding pin 5. The chief function 15 of the most advanced one of these pins is to prevent the rod 11 from dropping through the back run of the guide 3 after the sheet has been re-inverted, and to retain this rod in position to be engaged by the switch point 20 71. The rearmost pin 55 serves to push the rod 11 into the magazine if it tends to hang upon the switch point 71. These pins 55 are shorter than the pins 5, that is, they do not extend outward far enough to engage 25 any of the mechanisms as 71, 79, 44, 45, 76 and 6, some of which are engaged by the pins 5. The pins 5 constitute the feed means and constitute also the timing means by which the operation of the various mechanisms is co-ordinated.

What I claim as my invention is:

1. A display apparatus comprising a magazine adapted to hold a plurality of independent, flexible sheets in inverted position, sheet guides, feed means movable in an endless path about said magazine, said feed means being engageable with the reversed top edge of a sheet to remove it from the magazine, and cooperating with said guides to reverse it and to advance it into display position, to again reverse it, and finally to return it to the magazine in inverted position.

2. A display apparatus comprising a magazine adapted to hold a plurality of independent, flexible sheets in inverted position, sheet guides, feed means movable in a closed path about said magazine, said feed means being engageable with the reversed top edge 50 of a sheet to remove it from the magazine, and cooperating with said guides to reverse it and to advance it into display position, to again reverse it, and finally to return it to the magazine in inverted position, and selector means timed with the feed means for disposing a sheet in position for engagement with said feed means, and means for disengaging the sheet from the feed means to permit its return to the magazine.

3. In a display apparatus, in combination with a flexible display sheet having transverse rods at top and bottom, a magazine for receiving said sheet in inverted position comprising pairs of tracks for receiving the top

and bottom rods thereof, respectively, feed 65 means movable in a closed path including the reception point and the delivery point of said magazine, and engageable with the top rod of said sheet to remove the sheet from the magazine, to re-invert it and move 70 it into display position, and finally to invert the sheet and return it, inverted, to the magazine.

4. In a display apparatus, in combination with a flexible display sheet having transverse rods at top and bottom, a magazine for receiving said sheet in inverted position comprising pairs of tracks for receiving the top and bottom rods thereof, respectively, feed 75 means movable in a closed path including the reception point and the delivery point of said magazine, and engageable with the top rod of said sheet to remove the sheet from the magazine, to re-invert it and move 80 it into display position, and finally to invert the sheet and return it, inverted, to the magazine, said feed means also including restraining means positioned to restrain the bottom rod of the sheet.

5. In a display apparatus, in combination with a flexible display sheet having transverse rods at top and bottom, a magazine for receiving said sheet in inverted position comprising pairs of tracks for receiving the top and bottom rods thereof, respectively, feed 90 means movable in a closed path including the reception points of both pairs of tracks, and the delivery point of the lower pair of tracks, and engageable with the lowermost or top rod of said sheet at the delivery point 95 of the lower pair of tracks to remove the sheet from the magazine, sheet guides, said guides and the feed means cooperating to re-invert the sheet, to move it into display position, to invert it again, and to deliver the 100 top and bottom rods thereof again to the reception points of the lower and upper pairs of tracks, respectively.

6. In a display apparatus, in combination with a flexible display sheet having transverse rods at top and bottom, respectively, a magazine for receiving said sheet in inverted position comprising pairs of tracks for receiving the top and bottom rods thereof, respectively, feed means movable in a closed path including the delivery point of the magazine and its reception point, including the reception ends of both upper and lower tracks, said feed means being engageable with the lowermost or top rod of the sheet to remove the sheet from the magazine, move it into display position, and return it in inverted position with its top and bottom rods presented to the reception points of the lower and upper tracks, respectively, 120 and a switch member adjacent the reception point of the upper pair of tracks and normally positioned to permit passage of a rod,

and timed with said feed means to move into position to intercept the bottom rod following passage of the top rod.

7. A display device as in claim 6, the 5 switch member being engageable by the feed member after the top rod is clear of the switch, to be moved thereby into position to intercept the bottom rod.

8. In combination with a display apparatus as in claim 6, a diverter fixed in the path 10 of the top rod adjacent the reception point of the lower pair of tracks, and engageable with the top rod to disengage it from the feed means and to direct it into the magazine.

9. A display device as in claim 6, the switch member being engageable by the feed member after the top rod is clear of the switch, to be moved thereby into position 20 to intercept the bottom rod, and a diverter fixed in the path of the top rod adjacent the reception point of the lower pair of tracks, and engageable with the top rod substantially simultaneously with the engagement 25 of the bottom rod with said switch member, whereby the rods are simultaneously disengaged from the feed means and received by their respective magazine tracks.

10. In combination with a display device 30 as in claim 6, a switch-return device timed with the feed means and operatively connected with said switch member to return the same to normal position following its interception of the bottom rod.

35 11. A display device as in claim 6, the switch member being engageable by the feed member after the top rod is clear of the switch, to be moved thereby into position to intercept the bottom rod, a diverter positioned adjacent the reception point of the lower pair of tracks and engageable with the top rod to disengage it from the feed means, and a switch-return means positioned 40 in the path of the feed means and operable thereby after return of the sheet to the magazine to reset the switch member in normal position.

12. In a display apparatus for a plurality 50 of independent, flexible sheets, a guide for said sheets comprising a track for maintaining single sheets in position for endwise movement, the initial portion of said track including means engaging the uppermost portion of a sheet to restrain it from falling, 55 a magazine interposed between the ends of said track and comprising means permitting bodily lateral movement of the sheets, and sheet feed means engageable with the lowermost portion of a sheet positioned in the initial portion of the track to advance it into and from display position, said sheet guide including means for inverting a sheet following its engagement by the feed means and before positioning the sheet in display po-

sition, and for reinverting it prior to its delivery therefrom to the magazine. 65

13. In a display apparatus, in combination with a plurality of independent, flexible sheets, each having transversely extending top and bottom rods, a guide for said sheets 70 comprising a track for said rods, for maintaining single sheets in position for endwise movement, a magazine interposed between the ends of said track, and including upper and lower pairs of tracks for receiving the 75 bottom and top rods, respectively, of the sheets, said track including an initial section including the delivery ends of both magazine tracks, and arranged to restrain the uppermost or bottom rod from falling, and 80 sheet feed means movable in a closed path including the lowermost portion of the initial section, and the remainder of the sheet-guiding track, and engageable with the lowermost or top rod of a sheet positioned in 85 said initial section of track, thereby to advance the sheet.

14. In combination with a display device as in claim 13, a selector operable to deliver 90 a single sheet from the magazine to the initial section of the track, in position for engagement by the feed means.

15. In combination with a display device as in claim 13, a selector controlling the delivery of single sheets from the magazine to 95 the initial section of the track, in position for engagement of its top rod by the feed means, and means engageable by said feed means in its advance to operate said selector.

16. In combination with a display device 100 as in claim 13, a selector controlling the delivery of single sheets from the magazine to the initial section of the track, in position for engagement of its top rod by the feed means, means engageable by said feed means 105 in its advance to operate said selector, and means engageable by the feed means after operation of said selector and prior to engagement of the sheet's top rod, to insure return of said selector to normal position. 110

17. In combination with a display device as in claim 13, switch mechanism positioned 115 in the path of said feed means adjacent the receiving point of said magazine for disengaging the sheet from the feed means, and switch-control means engageable by said feed means as it advances.

18. In combination with a display device as in claim 13, a selector controlling the delivery of single sheets from the magazine to the initial section of the track, in position for engagement of its top rod by the feed means, means engageable by said feed means 120 in its advance to operate said selector, means engageable by the feed means after operation of said selector and prior to engagement of the sheet's top rod, to insure return of said selector to normal position, switch mecha-

nism positioned in the path of said feed means adjacent the receiving point of said magazine for disengaging the sheet from the feed means, and switch-control means engageable by said feed means as it advances.

19. A display device including an endless chain and guides therefor, a magazine included within the run of said chain, and comprising inclined tracks for receiving a plurality of rods each secured in an uppermost edge of a flexible display sheet, means for selecting a single rod at a time from said tracks, guide means for said sheets, and means carried by said chain for operating said selector and for engaging the lowermost edge of the selected sheet to advance such sheet along said guide means into display position, said guide means and said chain-carried means then cooperating to deliver the selected sheet to the receiving point of said magazine with its previously uppermost edge again at the upper end of the inclined tracks.

20. A display device including an endless chain and guides therefor, a magazine within the run of said chain comprising upper and lower pairs of inclined tracks for receiving opposite ends of two rods secured in the bottom and top edges, respectively, of a flexible sheet, means for separating the uppermost and lowermost rods of a given sheet simultaneously from the magazine, and for positioning the lowermost rod in the path of said chain, a pin carried by said chain and engageable with said lowermost rod, and a guide in general following the run of the chain, said pin and said guide cooperating to advance the sheet into display position, and then into position to be received by the receiving ends of the magazine tracks.

21. In combination with a display device as in claim 20, a switch mechanism positioned in the path of said chain and adjacent the receiving end of the upper magazine track, means engageable by said pin for moving said switch, after passage of the pin-engaged rod of the sheet, from its normal position into position to intercept the following rod, and other means engageable by said pin thereafter and after diversion of the following rod by said switch to throw said switch into its normal position.

22. In combination with a display device as in claim 20, means positioned in the path of the pin, and engageable thereby as it approaches the delivery end of the magazine, to operate said selector, and thereafter further engageable by the pin, prior to its engagement with the rod, to insure return of said selector to its normal position.

23. A display device as in claim 20, the chain having a pair of pins spaced from each other and from the first pin to receive the bottom or following rod of the advanc-

ing sheet, and to maintain the bottom edge of the sheet aligned with the run of the chain.

24. A display device as in claim 20, the chain having a pair of pins spaced from each other and from the first pin to receive the bottom or following rod of the advancing sheet, and to maintain the bottom edge of the sheet aligned with the run of the chain, selector and switch mechanisms for directing the sheet and its rods into and from engagement with the first pin, control means therefor including members positioned in the path of said pins, the pair of pins projecting less than the first pin and passing beneath said control means.

25. A method of handling display sheets delivered from and received by a magazine, which comprises bodily moving a sheet forwardly from the magazine, then moving it downward endwise, reversing it and moving it upward into display position, again reversing it through endwise movement, and finally moving it bodily forward into and through the magazine with the top edge lowermost.

26. In a display mechanism, in combination, an intermittently recurring display sheet, a plurality of independent display sheets, and means for controlling movement of each of said series of sheets in turn into display position, and therefrom, and for moving said recurring display sheet into display position during movement of sheets in the series, said control means comprising a master gear, two pins carried thereby, a slotted wheel engageable by each of said pins in succession to advance it intermittently in opposite directions, operative connections between said wheel and the recurring display sheet, a second slotted wheel engageable by one of said pins to advance it intermittently in the same direction, and operative connections between said second wheel and the feed means for said series of display sheets.

27. In a display apparatus for a plurality of independent, flexible sheets, a magazine including means for supporting and permitting bodily lateral movement of the sheets, means for guiding said sheets from said magazine to and past a display position, and back to the magazine, said guide means including an initial portion adapted to suspend a single sheet by its upper edge, and sheet-selecting means engageable with the depending portion of a sheet which is held in the initial portion of the guide means to pull it downward therefrom to initiate its advance.

28. A display device including an endless chain and guides therefor, a magazine within the run of said chain comprising upper and lower pairs of inclined tracks for receiving opposite ends of two rods secured

in the bottom and top edges, respectively, of a flexible sheet, means for separating the uppermost and lowermost rods of a given sheet simultaneously from the magazine, 5 and for positioning the lowermost rod in the path of said chain, a pin carried by said chain and engageable with said lowermost rod, and a guide in general following the run of the chain, said pin and said guide co- 10 operating to advance the sheet into display

position, and then into position to be received by the receiving ends of the magazine tracks, and a second pin carried by the chain and spaced from the first pin to position it in advance of the following rod of 15 the sheet, to prevent collapse of the sheet when inverted.

Signed at Seattle, King County, Washington, this 28th day of September, 1925.

HARRIS G. WARD.
